KNOB FACE OR SIMILAR ARTICLE

Fred J. Russell, Los Angeles, Calif.

Application February 24, 1956, Serial No. 40,321

Term of patent 14 years

(Cl. D50—3)

Fig. 1.

Fig. 2.

Fig. 3.

Figure 1 is a side view of a knob face embodying my new design.

Figure 2 is a front view.

Figure 3 is a sectional view.

The dominant features of the design reside in the portions shown in solid lines.

I claim:

The ornamental design for a knob face or similar article, as shown and described.
